N. GREENWELL

PROJECTILE

Filed Feb. 5, 1924

UNITED STATES PATENT OFFICE.

NEVIL GREENWELL, OF BETHLEHEM, PENNSYLVANIA, ASSIGNOR TO BETHLEHEM STEEL COMPANY.

PROJECTILE.

Application filed February 5, 1924. Serial No. 690,741.

To all whom it may concern:

Be it known that I, NEVIL GREENWELL, a citizen of the United States, residing at Bethlehem, county of Northampton, and

5 State of Pennsylvania, have invented a new and useful Improvement in Projectiles, of which the following is a full, clear, and exact description, reference being had to the accompanying drawings, which form a part 10 of this specification.

The present invention relates to improvements in armor piercing projectiles. In practice it has been found heretofore that in penetrating armor obliquely, the cavity 15 wall of the shell adjacent the base thereof is frequently ruptured. It is the principal aim of the present invention to produce an armor piercing projectile which will penetrate modern armor on oblique impact 20 without rupture of the cavity wall, and at the same time none of the ballistic properties shall be sacrificed.

To these ends the projectile may be constructed so that parts adjacent the base 25 end thereof are adapted to be removed or sheared off when penetrating the armor, thereby reducing the diameter of the body of the projectile adjacent said end.

It is recognized by those versed in the 30 ordnance ballistic art that irregularities to the exterior surface of the projectile should be avoided as much as possible and it is the object of this invention to provide a projectile having a weakened base portion 35 and at the same time conform to standard design wherein the exterior cylindrical surface at the rear of the rotating band is uninterrupted. It should be understood that the method usually employed to assemble the rotating bands in a groove cut 40 in the cylindrical surface of the projectile and adjacent the base thereof, is to provide a ring of copper, of uniform thickness, having an internal diameter less than the 45 exterior diameter of the projectile, to expand the ring by heat until the expansion of the ring is sufficient to allow same to be slipped over the projectile contiguous with said groove. The band is then placed 50 in dies under a press and the ring is pressed into its seat under great pressure and the copper flows and contacts firmly with the walls of its seat. Then the band is machined exteriorly to the desired profile. 55 This method of applying bands to projec-

tiles not only seats the bands firmly in place but also toughens the copper materially and makes it homogeneous which is very desirable.

The above described method of assembling bands to the projectile body subjects the walls of the band seat to high stresses and it is the main object of this invention to provide a projectile conforming to standard exterior contour having a frangible base 60 and a band seat having integral walls of solid construction.

My integral wall construction aforesaid further provides a substantial support for the rotating band when the latter engages 70 the rifling of the gun from which the projectile is fired.

The preferred embodiments of the invention are shown in the accompanying drawing, in which— 75

Figure 1 is a side elevation of the projectile;

Figure 2 is a longitudinal part section, illustrating my preferred form of frangible base end; 80

Figure 3 is similar to Figure 2 and illustrates an alternate method of attaching the base ring; and

Figure 4 is similar to Figure 2 and illustrates another embodiment of my invention. 85

In the drawings, I show a projectile 10 having a rotating band 11 fitting in a groove 12, formed in the body of the projectile. The body 10 is reduced in diameter at the rear of 90 the groove 12 from the base to a shoulder 13 and forms with the wall 14 a frangible collar 15. Preferably this latter collar should be only of sufficient thickness to withstand the pressure to which it is subjected when 95 the rotating band is being pressed firmly to its seat in the groove 12. Seated on the reduced portion of the body at the rear of the band is a ring 16 which is attached to the body by a means which is sufficiently strong 100 to allow for rough handling in transportation but which is easily frangible when subjected to such forces as may be encountered when the projectile penetrates armor. In Figure 2 the frangible ring portion 16 of the 105 projectile is attached to the body portion by means of pins 17, while in Figure 3 the ring is attached by means of threaded engagement with the body portion as at 18. In Figure 4 the ring is retained in position 110

by being made integral with the base plug 19 which is a usual component of a projectile of the armor piercing type. In the latter type of fastening, a weakening groove 20 is provided to facilitate the fracture between the ring of the base plug proper so that the firm seating of the plug in the body is not disturbed when the projectile penetrates the armor. In operation, when the projectile perforates the armor plate obliquely the projectile takes more or less a diagonal path and is subjected to high transverse stresses as the projectile tends to spin up a right angle to the surface of the plate and produce a normal perforation. This tendency to right itself becomes intense as the projectile emerges from the rear of the plate and the lateral stress imposed at the base before it emerges is so great that the rear end of the body would fracture and would most probably expose the projectile cavity, which is undesirable, were it not for the provision of the frangible collar 15 and the detachable ring portion 16, which are immediately sheared off the body proper which continues its flight essentially intact until exploded by the usual means provided.

Having now fully described my invention, what I claim and desire to protect by Letters Patent is:

1. A projectile comprising a shell body having a band seat and a reduced portion disposed rearwardly of the seat, a frangible collar separating the seat from the reduced portion, a band in the seat, a filler ring on the reduced portion, and a frangible connection between the filler ring and said body.

2. A projectile comprising a shell body having a band seat and a reduced portion disposed rearwardly of the seat, a frangible collar integral with said body separating the seat from the reduced portion, a band in

the seat, a filler ring on the reduced portion, and a frangible connection between the filler ring and said body.

3. A projectile comprising a shell body having a band seat and a reduced portion disposed rearwardly of the seat, a band in the seat, a frangible collar separating the seat from the reduced portion, said collar constituting the rear wall of said seat and being sufficiently rigid to support the band during the assembling step and frangible when subjected to excessive forces, a filler ring mounted on the reduced portion, and a frangible connection between the ring and said body.

4. A projectile comprising a shell body having a band seat and a reduced portion disposed rearwardly of the seat, a frangible collar separating the seat from the reduced portion, a band in the seat, a plug threaded in the base opening of the projectile, a filler ring mounted on the reduced portion and projecting rearwardly from body co-planar with the rear face of the plug and a frangible connection between the ring and the plug.

5. A projectile comprising a shell body having a band seat, a band in said seat, the body having a reduced portion disposed at the rear of the seat, a frangible collar separating the seat and the reduced portion to normally support the rearward thrust of the band, a ring mounted on the reduced portion and abutting the rear face of said collar, said ring extending to the base of the projectile and having an external diameter substantially the same as the outside diameter of the body, and a frangible connection between the ring and said body.

In testimony whereof I hereunto affix my signature this 30th day of January 1924.

NEVIL GREENWELL.
